CLEAT ATTACHMENT

Frederick A. McDunnah, Hampton, Falls, N. H.

Application December 28, 1943, Serial No. 515,918

1 Claim. (Cl. 248—74)

This invention relates to a new article of manufacture consisting of a metallic cleat attachment for application to a wall, floor, deck or other metallic structure to serve as a holder for another object such, for example, as a cable, pipe conduit or the like, the purpose of the invention being to provide a device of the character indicated which will be of simple, inexpensive and efficient construction and which may be quickly and easily secured in position upon the metallic structure or fixture to which it is applied, and also readily engaged with the object it is to hold.

To these ends I have provided a metallic cleat attachment of the character described which, in its preferred form, may be constructed and utilized as set forth in the following description, the several novel features of the invention being particularly pointed out and defined in the claim at the close of said description.

In the accompanying drawing—

Figure 1 is a top plan view of a cleat attachment constructed in accordance with this invention.

Figure 2 is a side view of the cleat attachment shown in Fig. 1.

Figure 3 is an end elevation of the cleat attachment shown in Figs. 1 and 2.

Figure 4 shows the cleat attached to a metallic floor and also illustrates the preferred method of engaging the cleat with the object it is to hold or support.

Figure 5 shows the condition of the cleat of Fig. 4 after it has been engaged with the object it is to hold or support.

The illustrated embodiment of my invention is made from a T-shaped sheet metal blank that is preferably bent into the shape shown in Figs. 1, 2 and 3 by means of dies, said embodiment comprising a body portion that is indicated generally at 10 and which is of inverted U-shape as viewed from either end and at one end of the top of this body portion is a cantilever tang extension 11.

The U-shaped body portion 10 is formed with an oblong top wall 12 and two parallel side walls or legs 13 depending perpendicularly from the opposite sides of said top wall, said side walls or legs being preferably of equal length and provided at their lower ends with straight edges which are parallel with the top wall 12.

The tang 11 is an extension of one end of the top wall 12 and is preferably formed adjacent to its free end with a downwardly facing hook 14 and at its extremity with an upwardly facing abutment shoulder 15 provided by an end lip 55

16. That is to say, the hook 14 faces in one direction and the abutment shoulder in the opposite direction.

5 The top wall 12 may, as shown, be molded with a longitudinal stiffening and strengthening rib 17.

10 As shown in Figs. 4 and 5 the legs 13 are seated upon and fastened by welding 18 to a metallic structure 19, such as the deck or wall of a ship, which is shown as provided with a top layer of cork or insulation 20, and when first welded in position the tang 11 occupies its initial elevated position shown in Figs. 2 and 4. Then the pipe conduit, electric cable, or other like object that 15 is to be secured in position by the cleat, is placed in position beneath hook 14 after which the tang 11 is bent downwardly on to the same into the position shown in Fig. 5. In the drawing the object to be secured in position is shown as a 20 pipe conduit 21.

25 To effect the bending of the tang I may employ a specially constructed lever that is indicated by broken lines at 22, said lever being made at its one end with a hook 23 to engage one end of the top wall 12 of body 10 as shown, and at its opposite end with a handle 24 which is grasped by hand and forced downwardly toward structure 19 to cause a shoulder 25 on the lever, intermediate the ends thereof, to engage the abutment shoulder 15 at the free end of the tang to bend the latter downwardly into the position shown in Fig. 5 where the pipe conduit 21 is fitted snugly into the hook of the tang. Or, the tang 11 may 30 be initially produced in its operative or holding position as shown in Fig. 5 in which case the lever may be dispensed with and the legs 13 of the cleat welded to structure 19 while the held object 21 occupies a position within the hook 14 of the tang.

35 40 45 50 What I claim is:

A cleat attachment for connecting an electric cable, a conduit or like object to a supporting wall structure or the like that includes a metallic element, said attachment being made from metal and comprising a body having a top wall, two oppositely disposed side walls projecting angularly from opposite sides of said top wall to serve as supporting legs whose extremities are seated upon and integrated with said metallic element by welding, and a hook extension at one end of said top wall by which said object is embraced and confined in a fixed position against said supporting wall structure.

FREDERICK A. McDUNNAH.
